CLASP

Gabriel S. Hawie, Bridgeport, Conn., assignor to
 The Hawie Manufacturing Co., Bridgeport,
 Conn., a corporation of Connecticut

Application March 11, 1940, Serial No. 323,447

4 Claims. (Cl. 24—250)

This invention pertains to clasps of the type used with suspenders, garment supporters, etc., and more especially to improvements in clasps of the kind disclosed in my Patent 2,141,983, dated 5 December 27, 1938. In that patent I have shown a clasp that may be opened fully when a lever is lifted so that the clasp will accommodate materials of various thicknesses, from the thinnest to the thickest, ordinarily used in clothing or the 10 like. It has been found in practice that when such a clasp is closed on a solid article like a belt or button, the middle lever may be strained or distorted to such an extent as to cause the clasp to slip afterwards when closed on cloth or other 15 textile fabrics.

The primary purpose of the present invention is to eliminate such objection and to provide a clasp which will withstand such strains without impairing or destroying its practicability.

20 A further object is to produce a simple and inexpensive clasp and yet one which will be exceedingly effective for the purpose for which it is designed.

The exact nature of the invention together 25 with further objects and advantages thereof will be apparent from the following description taken in connection with the accompanying drawing, in which

Fig. 1 is a perspective view of my improved 30 clasp shown suspended from a portion of a suspender and clasping a piece of clothing.

Fig. 2 is a vertical sectional view of the clasp, partly in elevation, and showing the same in open position.

35 Fig. 3 is a similar view with the clasp in closed position, and shown gripping the clothing.

Fig. 4 is an exploded perspective view of the elements from which the clasp is made.

Fig. 5 is a sectional view taken on the line 40 5—5 of Fig. 3.

Fig. 6 is a view similar to Fig. 1 but showing a modification.

Referring to the drawing, 7 designates the back or stationary jaw, 8 the movable jaw or middle 45 piece, 9 the lever, and 10 the yoke of the clasp. All of these parts with the exception of the yoke are preferably made of thin stamped sheet metal and the movable jaw is somewhat resilient.

50 In accordance with the present invention, the parts 7 and 9 are substantially as shown in my above-mentioned patent with the exception that the part 7 of the present structure is provided with longitudinal or vertical corrugations 11 for strengthening purposes, and the edges 12 of the

lever are shortened to decrease the contact at this edge between the lever and the jaw 8.

The yoke, in the present invention, is preferably formed of a piece of wire and is open instead of being a complete loop. It is provided with substantially parallel extremities or legs 13, and is shaped to receive the flange 14 at the top of the back piece. The legs 13 form abutment means and are adapted to occupy the corners formed at the junctures of the back piece and its apertured ears 15.

The movable jaw, in the present case, is also altered. It is provided with a vertical slit 16 extending downwardly through the upper edge of the jaw into close proximity to its middle, and at each side of the slit, the jaw is provided with a vertically disposed corrugation 17. The ridges 18 (Fig. 5), formed by these corrugations, project toward the back plate 7 and abut against the legs 13 when the clasp is closed, so as to limit distortion of the jaw 8 and spreading of the upper end portion of the jaw. Of course, the slit 16 allows either one of the corrugated portions of the jaw to give relatively to the other so as to prevent any strain or bending of the jaw.

In assembling this structure, the yoke 10 is first slipped over the flange 14 until the legs 13 occupy positions between the ears 15. Then the jaw 8 is applied to the back piece by inserting the lugs 18a into the opening 19 and causing the lateral ears 20 of the jaw to rest on the upper edges of the ears 15. Then the lever 9 is applied in such a manner as to cause its tongue 21 to enter the enlarged portion 22 of the slit of the jaw, and finally oppositely extending lugs 23 of the lever are interlocked with the apertures 24 of the ears.

When the parts are thus assembled, and the lever 9 is swung in a counter-clockwise direction (Fig. 2), its edges 12 will push the jaw 8 into closed position until the parts assume the positions shown in Fig. 3. If during closing movement, the jaw should encounter a solid object which the teeth 25 cannot penetrate, the jaw will yield without becoming permanently distorted, and later if the clasp is applied to a piece of cloth or the like, the parts will function properly.

In Fig. 6, I have shown the upper end portion of the back piece 7 folded over and bent downwardly about the yoke and jaw in the form of a 50 protecting apron 26.

While I have disclosed what I now consider to be preferred embodiments of the invention in such manner that the same may be readily understood by those skilled in the art, the right is 55

hereby reserved to make all such changes as fairly fall within the scope of the following claims.

What I claim and desire to secure by Letters Patent is:

- 5 1. In a clasp of the type having a stationary jaw and a swingable jaw pivotally connected at their upper end portions and provided at their lower end portions with means for clamping a garment to the clasp, and a lever pivotally connected to the upper end portion of the stationary jaw and engageable with the movable jaw for moving that jaw toward the stationary jaw, the improvement comprising a slit in the movable jaw extending downwardly from its upper 10 edge to a position below its middle, projections on the upper portion of the movable jaw arranged at opposite sides of said slit and extending toward the stationary jaw, and abutment means positioned between said jaws and engageable by said 15 projections to limit spreading of the upper portion of the movable jaw.
- 20 2. In a clasp of the type having a stationary jaw and a swingable jaw pivotally connected at their upper end portions and provided at their lower end portions with means for clamping a garment to the clasp, and a lever pivotally connected to the upper end portion of the stationary jaw and engageable with the movable jaw for moving that jaw toward the stationary jaw, the 25 improvement comprising a slit in the movable jaw extending from its upper edge to a position adjacent its middle, projections on the upper portion of the movable jaw arranged at opposite sides of the slit and extending toward the stationary jaw, and a loop secured to the upper portion 30 of the stationary jaw and provided with depending legs arranged between the jaws and engaging said projections to limit spreading of the upper portion of the movable jaw.
- 35 3. A clasp comprising a stationary jaw and a swingable jaw, means pivotally connecting the

upper end portions of the jaws and constraining the movable jaw to swing about a fixed axis, means at the lower end of the jaws for clamping a garment to the clasp, a lever arranged substantially parallel to said jaws and having its upper 5 end pivotally connected to the upper end portion of the stationary jaw, the upper end portion of the lever being engageable with the swingable jaw for moving the latter toward and away from the stationary jaw, said swingable jaw having a 10 slit extending from its upper edge downwardly into close proximity to its middle, corrugations extending lengthwise of the swingable jaw at opposite sides of the slit and projecting toward the stationary jaw, and abutting means between 15 the jaws engaged by the corrugations for limiting spreading movement of the upper portion of the swingable jaw.

4. A clasp comprising a stationary jaw and a swingable jaw, means pivotally connecting the 20 upper end portions of the jaws and constraining the movable jaw to swing about a fixed axis, means at the lower end of the jaws for clamping a garment to the clasp, a lever arranged substantially parallel to said jaws and having its upper 25 end pivotally connected to the upper end portion of the stationary jaw, the upper end portion of the lever being engageable with the swingable jaw for moving the latter toward and away from the stationary jaw, said swingable jaw having a 30 slit extending from its upper edge downwardly into close proximity to its middle, corrugations extending lengthwise of the swingable jaw at opposite sides of the slit and projecting toward the stationary jaw, and a yoke pivotally connected 35 to the upper end portion of the stationary jaw and having depending legs arranged between the jaws and bearing against the outer sides of said corrugations.

GABRIEL S. HAWIE.
